IMAGE FORMING APPARATUS

CROSS-REFERENCE TO RELATED APPLICATIONS

This application is based upon and claims the benefit of priority from the corresponding Japanese Patent Application No. 2013-109231, filed on May 23, 2013, in the Japanese Patent Office. All disclosures of the document(s) named above are incorporated herein by reference.

BACKGROUND OF THE INVENTION

The present disclosure relates to an image forming apparatus such as a copier, a printer, and a facsimile machine, and relates particularly to an image forming apparatus capable of compatibly incorporating two kinds of developing devices employing different developing methods.

The following methods are included in conventionally known developing methods involving use of dry toner and employed in an image forming apparatus using electrophotographic process: a one-component developing method in which no carrier is used, and a two-component developing method (hereinafter also referred to as a first developing method) in which a two-component developer including a magnetic carrier (hereinafter also referred to simply as carrier) and non-magnetic toner that is electrostatically charged by the magnetic carrier is used to develop an electrostatic latent image on a photosensitive body by using a magnetic brush of the toner and the carrier formed on a magnetic roller.

Further, in cases of color printing, where color superimposition is performed, color toner having transparency needs to be used, and thus the color toner is required to be non-magnetic toner. For this reason, full-color image forming apparatuses often adopt the two-component developing method where toner is conveyed and electrically charged by using a carrier.

On the other hand, there has been proposed a developing method (hereinafter referred to also as a second developing method) where, when a developer is transferred, by using a magnetic roller (a developer carrier), onto a developing roller (a toner carrier) disposed out of contact with an image carrier (a photosensitive body), non-magnetic toner alone is transferred onto the developing roller to form a thin toner layer thereon, with a magnetic carrier left on the magnetic roller, and the toner is caused to adhere to an electrostatic latent image on the image carrier (the photosensitive body) by an alternating-current electric field.

There has been also proposed a developing device where a developer including a carrier is supplied into a developing container and surplus part of the developer is discharged, to thereby reduce degradation of the charging performance. A known example of such a developing device is one that is provided with supply means that performs additional supply of a developer via a supply port formed in a developing container, and a developer discharging mechanism that discharges the surplus part of the developer to outside the developing container.

SUMMARY OF THE INVENTION

According to one aspect of the present disclosure, an image forming apparatus includes an image forming section that includes an image carrier and a developing device, and a developer recovery mechanism. On the image carrier, an electrostatic latent image is formed. The developing device is provided corresponding to the image carrier, has a developing

2

container for accommodating a two-component developer including magnetic carrier and toner, a developer carrier rotatably supported in the developing container, an agitation member that agitates and conveys the developer in the developing container, a supply member that agitates and conveys the developer received from the agitation member and supplies the developer to the developer carrier, a developer supply port through which the developer is supplied into the developing container, and a developer discharge portion that discharges surplus part of the developer out of the developing container. The developing device develops the electrostatic latent image formed on the image carrier. The developer recovery mechanism has a connection portion connected to the developer discharge portion, and recovers the surplus part of the developer discharged from the developing device. The image forming section is capable of selectively incorporating either one of: a developing device employing a first developing method where toner is caused to adhere to a surface of the image carrier by means of a magnetic brush formed on the developer carrier; and a developing device that has a toner carrier disposed between the developer carrier and the image carrier, and that employs a second developing method where a toner layer is formed on a surface of the toner carrier by means of a magnetic brush formed on the developer carrier and toner is caused to adhere to the surface of the image carrier, by means of the toner layer formed on the toner carrier. The developing device employing the first developing method and the developing device employing the second developing method, in a state of being installed in the image forming device, have a same positional relationship of the developer discharge portion with respect to a rotation shaft of the image carrier.

Still other objects and specific advantages of the present disclosure will become apparent from the following descriptions of preferred embodiments.

BRIEF DESCRIPTION OF THE DRAWINGS

40 These and/or other aspects and advantages of the invention will become apparent and more readily appreciated from the following description of the embodiments, taken in conjunction with the accompanying drawings of which:

45 FIG. 1 is a schematic sectional view showing an interior configuration of an image forming apparatus 100 according to a first embodiment of the present disclosure;

FIG. 2 is an enlarged sectional view showing the vicinity of an image forming section Pa in FIG. 1;

FIG. 3 is an enlarged sectional view showing the vicinity of an image forming section Pd in FIG. 1;

FIG. 4 is a side sectional view of developing devices 3a to 3c incorporated in image forming sections Pa to Pc, respectively, in the image forming apparatus 100 of the first embodiment;

55 FIG. 5 is a side sectional view of a developing device 3d incorporated in the image forming section Pd in the image forming apparatus 100 of the first embodiment;

FIG. 6 is a plan sectional view showing a configuration of agitating portions of the developing devices 3a to 3d;

60 FIG. 7 is a perspective view of a developer recovering mechanism 80 in the image forming apparatus 100 of the first embodiment;

FIG. 8 is a diagram showing a positional relationship between rotation shafts O of the photosensitive drums 1a to 1d and the agitation conveyance screws 31b of the developing devices 3a to 3d, respectively, in the image forming apparatus 100 of the first embodiment;

FIG. 9 is a diagram showing a positional relationship between the rotation shafts O of the photosensitive drums 1a to 1d and the supply conveyance screws 31a of the developing devices 3a to 3c and the agitation conveyance screw 31b of the developing device 3d in the image forming apparatus 100 of the first embodiment;

FIG. 10 is a side sectional view of the developing device 3d incorporated in an image forming section Pd in an image forming apparatus 100 according to a second embodiment of the present disclosure; and

FIG. 11 is a diagram showing a positional relationship of the supply conveyance screws 31a and the agitation conveyance screws 31b of the developing devices 3a to 3d as seen from the rotation shafts O of the photosensitive drums 1a to 1d, respectively, in the image forming apparatus 100 of the second embodiment.

DETAILED DESCRIPTION OF THE EMBODIMENTS

Hereinafter, embodiments of the present disclosure will be described with reference to the accompanying drawings. FIG. 1 is a sectional view showing a schematic configuration of an image forming apparatus 100 according to a first embodiment of the present disclosure. The image forming apparatus 100 of the present embodiment is a quadruple tandem type color printer operable to perform image formation with four photosensitive drums 1a, 1b, 1c, and 1d corresponding to 4 different colors (magenta, cyan, yellow, and black) and arranged parallel to each other.

In an apparatus main body of the image forming apparatus 100, four image forming sections Pa, Pb, Pc, and Pd are arranged in order from the left side in FIG. 1. These image forming sections Pa to Pd are provided corresponding to images of four different colors (magenta, cyan, yellow, and black, respectively), and the image forming sections Pa to Pd sequentially form magenta, cyan, yellow, and black images through steps of charging, exposing, developing, and transferring.

These image forming sections Pa to Pd are provided with photosensitive drums 1a to 1d, respectively, to carry visible images (toner images) of corresponding colors, and further, an intermediate transfer belt 8 that rotates in a counterclockwise direction in FIG. 1 is arranged in contact with the image forming sections Pa to Pd. The toner images formed on these photosensitive drums 1a to 1d are transferred one after another onto the intermediate transfer belt 8 moving in contact with the photosensitive drums 1a to 1d, and the thus transferred toner images are then transferred all at once onto paper P (recording medium) at a secondary transfer roller 9, and further, the toner images on paper P are fixed thereon at a fixing device 13, and then paper P is ejected to outside the image forming apparatus 100. The image forming process is performed on each of the photosensitive drums 1a to 1d while the photosensitive drums 1a to 1d are being made to rotate in a clockwise direction in FIG. 1.

The paper P onto which the toner images are transferred is accommodated in the paper cassette 16 disposed at a lower portion inside the image forming apparatus 100, and is conveyed to the secondary transfer roller 9 via a paper feeding roller 12a and a regist roller pair 12b. A dielectric plastic sheet is used as the intermediate transfer belt 8, which is typically formed as a jointless (seamless) belt. The intermediate transfer belt 8 and the secondary transfer roller 9 are driven to rotate by a belt driving motor (not shown) at the same linear velocity as the photosensitive drums 1a to 1d. For the purpose of removing toner and the like remaining on a surface of the

intermediate transfer belt 8, a belt cleaner 19 is disposed downstream from the secondary transfer roller 9. The belt cleaner 19 is a blade-like member.

Next, the image forming sections Pa to Pd will be described. Around and below the rotatably disposed photosensitive drums 1a to 1d, the following are provided: charging devices 2a, 2b, 2c, and 2d that charge the photosensitive drums 1a, 1b, 1c, and 1d, respectively; an exposure unit 5 that performs exposure on each of the photosensitive drums 1a to 1d based on image data; developing devices 3a, 3b, 3c, and 3d that develop, using toner, electrostatic latent images formed on the photosensitive drums 1a, 1b, 1c, and 1d, respectively; and cleaning devices 7a, 7b, 7c, and 7d that recover and remove a developer (toner) remaining on the photosensitive drums 1a, 1b, 1c, and 1d, respectively, after the toner images on the photosensitive drums 1a to 1d are transferred.

On receipt of image data from a host device such as a personal computer, first, the charging devices 2a to 2d uniformly charge the surfaces of the photosensitive drums 1a to 1d, respectively. Subsequently, based on the image data, the exposure unit 5 irradiates the photosensitive drums 1a to 1d with light to thereby form electrostatic latent images on the photosensitive drums 1a to 1d according to the image data. The developing devices 3a to 3d are provided with developing rollers (developer carriers) that are located to respectively face the photosensitive drums 1a to 1d. The developing rollers are each filled with a predetermined amount of two-component developer including toner of a respective color, that is, magenta, cyan, yellow, or black.

Note that, in a case where the proportion of toner in the two-component developers accommodated in the respective developing devices 3a to 3d falls below a set value after toner images are formed as described later, developers including toner are supplied to the developing devices 3a to 3d from containers 4a to 4d, respectively. The toner within each of the developers is supplied onto a corresponding one of the photosensitive drums 1a to 1d by the developing devices 3a to 3d, respectively, and electrostatically adheres thereto. Thereby, toner images are formed according to the electrostatic latent images formed by the exposure performed by the exposure unit 5.

Then, a predetermined transfer voltage is applied across primary transfer rollers 6a to 6d and the photosensitive drums 1a to 1d by the primary transfer rollers 6a to 6d, respectively, and thereby, the magenta, cyan, yellow, and black toner images formed on the photosensitive drums 1a to 1d are primarily transferred onto the intermediate transfer belt 8. The toner images of the four colors are formed to have a predetermined positional relationship therebetween that is previously determined for forming a predetermined full-color image. The primary transfer rollers 6a to 6d are driven to rotate by a primary transfer drive motor (not shown) at the same linear velocity as the photosensitive drums 1a to 1d and the intermediate transfer belt 8. Thereafter, in preparation for formation of new electrostatic latent images to be subsequently performed, the toner and the like remaining on the surfaces of the photosensitive drums 1a to 1d after the primary transfer are removed by the cleaning devices 7a to 7d, respectively.

The intermediate transfer belt 8 is wound around and between a driven roller 10 and a driving roller 11. When the intermediate transfer belt 8 starts to rotate counterclockwise in conjunction with rotation of the driving roller 11 caused by the above-mentioned belt driving motor, a sheet of paper P is conveyed from the regist roller pair 12b at a predetermined timing to a nip portion (a secondary transfer nip portion) between the intermediate transfer belt 8 and the secondary

transfer roller 9 disposed adjacent to the intermediate transfer belt 8. At the nip portion, the full-color image is transferred onto the sheet of paper P. The sheet of paper P onto which the toner image has been transferred is conveyed to the fixing device 13.

At the fixing device 13, heat and pressure are applied to the sheet of paper P when it passes through a nip portion (fixing nip portion) of a fixing roller pair 13a to fix the toner image on a side of the sheet of paper P, and thereby, the predetermined full-color image is formed. The sheet of paper P on which the full-color image has been formed is directed toward one of a plurality of conveying directions branched from a branching portion 14. In a case of forming an image only on one side of the sheet of paper P, the sheet of paper P is ejected as it is onto an ejection tray 17 by an ejection roller pair 15.

On the other hand, in a case of forming an image on each side of the sheet of paper P, the sheet of paper P that passed through the fixing portion 13 is conveyed such that part thereof temporarily projects to outside the apparatus from the ejection roller pair 15. Thereafter, the ejection roller pair 15 is caused to rotate reversely to thereby direct the sheet of paper P into a reverse conveying path 18 from the branching portion 14, and is conveyed back to the secondary transfer roller 9 with the image side reversed. Then, a next image formed on the intermediate transfer belt 8 is transferred by the secondary transfer roller 9 onto the unprinted side of the sheet of paper P, and then, after the sheet of paper P is conveyed to the fixing device 13, where the toner image is fixed on the sheet of paper P, the sheet of paper P is ejected by the ejection roller pair 15 onto the ejection tray 17.

Next, details of the above image forming sections Pa to Pd will be described. FIG. 2 and FIG. 3 are sectional views showing in an enlarged manner the vicinity of the image forming sections Pa and Pd, respectively, shown in FIG. 1. Note that detailed descriptions will be omitted of the image forming sections Pb and Pc, which are basically similar to the image forming section Pa in configuration. Around the photosensitive drums 1a to 1d, along a drum rotation direction (clockwise direction in FIGS. 2 and 3), the above-mentioned charging devices 2a to 2d, developing devices 3a to 3d, primary transfer rollers 6a to 6d, and cleaning devices 7a to 7d, respectively, are arranged. Among these, the primary transfer rollers 6a to 6d are respectively disposed to face the photosensitive drums 1a to 1d, respectively, with the intermediate transfer belt 8 therebetween.

Further, the photosensitive drums 1a to 1d, the charging devices 2a to 2d, and the cleaning devices 7a to 7d, respectively, are built as units. Note that, in the image forming sections Pa to Pd, units including the photosensitive drums 1a to 1d, the charging devices 2a to 2d, the cleaning devices 7a to 7d, respectively, will be hereinafter referred to as drum units 27a to 27d.

The charging devices 2a to 2d have charging rollers 21 that are in contact with the photosensitive drums 1a to 1d to apply a charging bias to surfaces thereof, and charge cleaning rollers 22 for cleaning the charging rollers 21.

The cleaning devices 7a to 7d each have a rubbing roller (polishing member) 23, a cleaning blade 24, and a recovery spiral 25. For example, the rubbing roller 23 of the drum unit 27a is pressed against the photosensitive drum 1a with a predetermined pressure, and is driven by a drum cleaning motor (not shown) to rotate in the same direction as the photosensitive drum 1a at a contact surface where the rubbing roller 23 is in contact with the photosensitive drum 1a, but the linear velocity of the rubbing roller 23 is controlled to be greater (here, 1.2 times greater) than that of the photosensitive drum 1a. An example of the structure of the rubbing rollers 23

is one in which a foam layer of an ethylene-propylene terpolymer (EPDM) rubber having an Asker C hardness of 55 degrees is formed as a roller body around a metal shaft. The material for the roller body is not limited to the EPDM rubber, and the roller body may be formed of a rubber of another material or a foamed rubber body, and a material having an Asker C hardness from 10 to 90 degrees is preferably used.

Here, the Asker C is one of the durometers (spring type hardness meter) specified in the Standard of the Society of Rubber Industry, Japan, and it is an instrument for measuring hardness. The Asker C hardness refers to hardness measured with the above-mentioned measuring instrument, and a harder material has a larger value of the Asker C hardness.

The cleaning blades 24 are fixed to be in contact with the surfaces of the photosensitive drums 1a to 1d at locations downstream from where the rubbing rollers 23 are in contact with the photosensitive drums 1a to 1d. As the cleaning blade 24, for example, a polyurethane-rubber blade having a JIS hardness of 78 degrees is used. The cleaning blades 24 are attached such that the cleaning blades 24 contact the photosensitive drums 1a to 1d at a predetermined angle with respect to tangential directions of the photosensitive drums 1a to 1d. Note that elements such as the material and the hardness of the cleaning blades 24, the size of the cleaning blades 24, how far the cleaning blades 24 sink into the photosensitive drums 1a to 1d, and with how much pressure the cleaning blades 24 are pressed against the photosensitive drums 1a to 1d are properly set according to the specifications of the photosensitive drums 1a to 1d. The JIS hardness refers to hardness specified in Japanese Industrial Standards (JIS).

Residual toner removed from the surfaces of the photosensitive drums 1a to 1d by the rubbing rollers 23 and the cleaning blades 24 is discharged to outside the cleaning devices 7a to 7d in conjunction with rotation of the recovery spirals 25. Examples of toner used in the present disclosure include toner whose particles have an abrasive agent selected from silica, titanium oxide, strontium titanate, alumina, and the like, embedded in the surfaces thereof such that the abrasive agent partially protrudes from the surfaces, and toner in which an abrasive agent is electrostatically attached on the surfaces of the toner particles.

By controlling the rubbing roller 23 to rotate at a speed different from the speed of the photosensitive drum 1a, the surface of the photosensitive drum 1a is polished by the residual toner including the abrasive agent, and moisture, corona products, and the like are removed from the drum surface, together with the residual toner, by the rubbing roller 23 and the cleaning blade 24.

The developing devices 3a to 3d develop electrostatic latent images formed on the photosensitive drums 1a to 1d, respectively, into toner images using the two-component developers (hereinafter also referred to simply as developers) each including toner and carrier.

Among the developing devices 3a to 3d, the developing device 3d disposed in the image forming section Pd has a supply conveyance screw 31a, an agitation conveyance screw 31b, and a magnetic roller 32 (developer carrier), and employs the first developing method in which the toner is caused to adhere to the surface of the photosensitive drum 1d by using a magnetic brush formed on the magnetic roller 32.

On the other hand, the developing devices 3a to 3c disposed in the image forming sections Pa to Pc, corresponding to magenta, cyan, and yellow, each have the supply conveyance screw 31a, the agitation conveyance screw 31b, the magnetic roller 32 (developer carrier), and a developing roller 33 (toner carrier), and employs the second developing method in which the toner is caused to fly onto the surfaces of the

photosensitive drums **1a** to **1c** by applying to the developing roller **33** a development bias of the same polarity (plus) as the toner charge polarity.

Next, detailed descriptions will be given of configurations of the developing devices **3a** to **3d**. FIG. 4 is a side sectional view of the developing devices **3a** to **3c**. As shown in FIG. 4, the developing devices **3a** to **3c** are each provided with a developing container **30** in which the developer is accommodated, and the developing container **30** is separated by a partition **30a** into a supply conveyance chamber **30b** and an agitation conveyance chamber **30c**. In the supply conveyance chamber **30b** and the agitation conveyance chamber **30c**, there are rotatably disposed a supply conveyance screw **31a** and an agitation conveyance screw **31b**, respectively, for charging by mixing and agitating the toner (positively-charged toner) and the carrier included in each of the developers respectively supplied from the containers **4a** to **4c** (refer to FIG. 1).

Then, the developer is conveyed in an axial direction (a direction perpendicular to the plane of FIG. 4), while being agitated, by the supply conveyance screw **31a** and the agitation conveyance screw **31b**, and the developer circulates in the supply conveyance chamber **30b** and the agitation conveyance chamber **30c** via developer passages **40a** and **40b** (see FIG. 6) respectively formed at two end portions of the partition **30a**. That is, the supply conveyance chamber **30b**, the agitation conveyance chamber **30c**, and the developer passages **40a** and **40b** together form a developer circulation path inside the developing container **30**.

The developing container **30** extends obliquely upward to the right in FIG. 4; inside the developing container **30**, the magnetic roller **32** is located above the supply conveyance screw **31a**, and the developing roller **33** is located obliquely upward to the right of, and facing, the magnetic roller **32**. Further, the developing roller **33** faces a corresponding one of the photosensitive drums **1a** to **1c** on an opening side (right side of FIG. 4) of the developing container **30**, and the magnetic roller **32** and the developing roller **33** rotates about respective rotation shafts in a counterclockwise direction in FIG. 4.

Inside the agitation conveyance chamber **30c**, there is provided a toner concentration sensor **41** facing the agitation conveyance screw **31**. Used as the toner concentration sensor **41** is a magnetic permeability sensor for detecting a magnetic permeability of the two-component developer including the toner and the magnetic carrier inside the developing container **30**. Here, the toner concentration represents a ratio (T/C) of the toner with respect to the magnetic carrier in the developer, and in the present embodiment, the toner concentration sensor **41** is configured to detect the magnetic permeability of the developer and output a voltage value corresponding to a result of its detection to a control section (not shown), which will be described later, and the toner concentration is determined by the control section based on an output value obtained from the toner concentration sensor **41**. The control section transmits to a supply motor a control signal corresponding to the determined toner concentration, and supplies the developing container **30** with a predetermined amount of developer through a developer supply port **30d** (see FIG. 6).

The magnetic roller **32** includes a non-magnetic rotation sleeve **32a** and a stationary magnet body **32b** disposed inside the rotation sleeve **32a** and having a plurality of magnetic poles (here, 5 poles). In the present embodiment, the stationary magnet body **32b** includes five poles, namely, a main pole **45**, a regulation pole (ear cutting magnetic pole) **46**, a conveying pole **47**, an exfoliation pole **48**, and a scooping pole **49**.

The developing roller **33** includes a cylindrical developing sleeve **33a**, and a developing roller-side magnetic pole **33b** fixed inside the developing sleeve **33a**, the developing roller **33** located facing the magnetic roller **32** with a predetermined gap therebetween at the facing position (opposing position). The developing roller-side magnetic pole **33b** has a polarity different from that of the opposing magnetic pole (main pole) **45** of the stationary magnetic body **32b**.

Further, an ear cutting blade **35** is attached to the developing container **30** along a longitudinal direction (direction perpendicular to the plane of FIG. 4) of the magnetic roller **32**, and the ear cutting blade **35** is positioned upstream from the opposing position where the developing roller **33** and the magnetic roller **32** face each other, in a rotational direction of the magnetic roller **32** (counterclockwise direction in FIG. 4). Further, a slight clearance (gap) is formed between an edge portion of the ear cutting blade **35** and a surface of the magnetic roller **32**.

A direct current voltage (hereinafter, referred to as V_{slv} (DC)) and an alternating current voltage (hereinafter, referred to as V_{slv} (AC)) are applied to the developing roller **33**, while a direct current voltage (hereinafter, referred to as V_{mag} (DC)) and an alternating current voltage (hereinafter, referred to as V_{mag} (AC)) are applied to the magnetic roller **32**.

As has been described above, the toner is charged while the developer is circulating inside the developing container **30** by being conveyed, while being agitated, by the supply conveyance screw **31a** and the agitation conveyance screw **31b**, and the developer is conveyed to the magnetic roller **32** by the supply conveyance screw **31a**. Then, a magnetic brush is formed on the magnetic roller **32** with the carrier and toner particles adhering to each other, and the magnetic brush on the magnetic roller **32** has its layer thickness regulated by the ear cutting blade **35**. Thereafter, the magnetic brush is conveyed to an opposing portion where the magnetic roller **32** and the developing roller **33** face each other, and a thin toner layer is formed on the developing roller **33** based on a potential difference ΔV between V_{mag} (DC) applied to the magnetic roller **32** and V_{slv} (DC) applied to the developing roller **33**, and a magnetic field.

Although the toner layer thickness on the developing roller **33** changes with, for example, resistance of the developer, the rotation speed difference between the magnetic roller **32** and the developing roller **33**, the toner layer thickness is able to be controlled by the potential difference ΔV . The larger the potential difference ΔV is made, the thicker the toner layer becomes on the developing roller **33**, while the smaller the potential difference ΔV is made, the thinner the toner layer becomes on the developing roller **33**. An appropriate range of the potential difference ΔV for development is typically on the order of 100 V to 350 V.

The thin toner layer formed on the developing roller **33** by the magnetic brush is conveyed by rotation of the developing roller **33** to the opposing portion where the corresponding one of the photosensitive drums **1a** to **1c** faces the developing roller **33**. Since V_{slv} (DC) and V_{slv} (AC) are applied to the developing roller **33**, the toner is caused to fly from the developing roller **33** to the corresponding one of the photosensitive drums **1a** to **1c** by the potential difference with respect to the surface potential of the corresponding one of the photosensitive drums **1a** to **1c**, and thereby an electrostatic latent image is formed on each of the photosensitive drums **1a** to **1c**.

The toner left without being used for development is again conveyed by the rotation of the developing roller **33** at the opposing portion where the developing roller **33** and the magnetic roller **32** face each other, and is recovered by the magnetic brush on the magnetic roller **32**. Subsequently, after

being exfoliated from the magnetic roller 32 at portions of a same polarity (the exfoliation pole 48, the scooping pole 49) of the stationary magnet body 32b, the magnetic brush is brought back into the two-component developer circulating in the supply conveyance chamber 30b and the agitation conveyance chamber 30c. Then, as a two-component developer electrically charged uniformly and having a proper toner concentration, the two-component developer forms a magnetic brush on the magnetic roller 32 to be conveyed to the ear cutting blade 35.

FIG. 5 is a side sectional view of the developing device 3d. As shown in FIG. 3, the developing container 30 where the developer is accommodated is separated by the partition 30a into the supply conveyance chamber 30b and the agitation conveyance chamber 30c. And, the supply conveyance screw 31a is disposed in the supply conveyance chamber 30b, and the agitation conveyance screw 31b is disposed in the agitation conveyance chamber 30c. The developer supply port 30d (see FIG. 6) is provided in an upper portion of the developing container 30, and the developer accommodated in the container 4d (see FIG. 1) is supplied according to the detection result of the toner concentration sensor 41 (not shown) that detects the amount of the toner in the developing container 30.

The supply conveyance screw 31a and the agitation conveyance screw 31b each have a configuration in which a spiral blade is provided on the circumferential surface of a shaft, and are rotatably supported to be parallel to each other in the developing container 30. The partition 30a does not exist at both ends portions in a longitudinal direction (direction perpendicular to the plane of FIG. 5) of the developing container 30, the longitudinal direction being an axial direction of the supply conveyance screw 31a and the agitation conveyance screw 31b, but instead, developer passages 40a and 40b (see FIG. 6) are formed. The developer passages 40a and 40b allows delivery of the developer between the supply conveyance screw 31a and the agitation conveyance screw 31b, and the agitation conveyance screw 31b conveys toner existing in the agitation conveyance chamber 30c, while agitating the toner, into the supply conveying chamber 30b, and the supply conveyance screw 30a supplies the developer that has been conveyed into the supply conveyance chamber 30b, while agitating the developer, to the magnetic roller 32.

The magnetic roller 32 is rotatably supported in the developing container 30 to be parallel with the supply conveyance screw 31a and the agitation conveyance screw 31b. The magnetic roller 32 includes a non-magnetic, rotation sleeve 32a and a stationary magnet body 32b disposed inside the rotation sleeve 32a and having a plurality of magnetic poles (here, 5 poles). A developer is caused to adhere to (be carried on) the surface of the rotation sleeve 32a by the magnetism of the stationary magnet body 32b, and thereby a magnetic brush is formed. Part of the circumferential surface of the magnetic roller 32 is exposed from the developing container 30, and the magnetic roller 32 is disposed such that the exposed portion faces the photosensitive drum 1d.

The ear cutting blade 35 is formed such that its longitudinal length is greater than a maximum development width of the magnetic roller 32, and by being disposed a predetermined distance away from the magnetic roller 32, the ear cutting blade 35 regulates the amount of toner supplied to the photosensitive drum 1d. The distance between the magnetic roller 32 and the ear cutting blade 35 is set to be on the order of 0.1 mm to 2 mm. The material of the ear cutting blade 35 is, for example, magnetic or non-magnetic stainless steel (SUS).

The regulation pole (for example, N pole) of the stationary magnet body 32b faces the ear cutting blade 35, an opposite polarity (S pole) is induced at an edge of the ear cutting blade

35, and thus an attracting magnetic field is generated between the magnetic roller 32 and the ear cutting blade 35. By means of this magnetic field, a magnetic brush is formed between the ear cutting blade 35 and the magnetic roller 32. Then, when the magnetic roller 32 rotates clockwise in FIG. 5 to cause the magnetic brush to move to a position facing the photosensitive drum 1d, the magnetic brush touches the surface of the photosensitive drum 1d to form a toner image.

Next, a detailed description will be given of an agitating portion of the developing devices 3a to 3d. The configuration of the agitating portion is basically the same for the developing devices 3a to 3c shown in FIG. 4 and the developing device 3d shown in FIG. 5, and thus the following description of the agitating portion is common to the developing devices 3a to 3d. FIG. 6 is a plan sectional view (sectional view as seen from the arrow direction of X X' line of FIG. 4 and FIG. 5) showing the agitating portion of the developing devices 3a to 3d.

As mentioned above, by means of the partition 30a, the supply conveyance chamber 30b, the agitation conveyance chamber 30c, and the developer passages 40a and 40b are formed in the developing container 30, and in addition, the developer supply port 30d and a developer discharge portion 30e are formed in the developing container 30. It should be noted that, in the supply conveyance chamber 30b, the left side in FIG. 6 is the upstream side and the right side in FIG. 6 is the downstream side in the supply conveyance chamber 30b, while the right side in FIG. 6 is the upstream side and the left side in FIG. 6 is the downstream side in the agitation conveyance chamber 30c. Thus, the developer passages 40a and 40b are referred to with upstream-side and downstream-side, respectively, with respect to the agitation conveyance chamber 30c.

The partition 30a extends in the longitudinal direction of the developing container 30 to separate the supply conveyance chamber 30b and the agitation conveyance chamber 30c from each other to be disposed side by side. The right end portion of the partition 30a in the longitudinal direction, together with an interior wall portion of the developing container 30, forms the upstream-side developer passage 40a, and on the other hand, the left end portion of the partition 30a in the longitudinal direction, together with the interior wall portion of the developing container 30, forms the downstream-side developer passage 40b. This allows the developer to circulate through inside the supply conveyance chamber 30b, the developer passage 40a, the agitation conveyance chamber 30c, and the developer passage 40b.

The developer supply port 30d is an opening for supplying anew developer into the developing container 30 from a corresponding one of the containers 4a to 4d (see FIG. 1) provided in the upper portion of the developing container 30, and the developer supply port 30d is disposed on the upstream side (left side in FIG. 6) of the supply conveyance chamber 30b.

The developer discharge portion 30e is an opening for discharging surplus part of the developer in the supply conveyance chamber 30b and the agitation conveyance chamber 30c, and the developer discharge portion 30e is provided downstream from the agitation conveyance chamber 30c to be continuously provided in the longitudinal direction of the agitation conveyance chamber 30c.

The supply conveyance chamber 30b has the supply conveyance screw 31a disposed therein, and the agitation conveyance chamber 30c has the agitation conveyance screw 31b disposed therein. The supply conveyance screw 31a has a rotation shaft 41a and a spiral blade 43a that is integral with the rotation shaft 41a and spirally formed in the axial direc-

11

tion of the rotation shaft 41a at a constant pitch. The agitation conveyance screw 31b has a rotation shaft 41b and a spiral blade 43b that is integral with the rotation shaft 41b and spirally formed in the axial direction of the rotation shaft 41b at a constant pitch. The spiral blade 43b of the agitation conveyance screw 31b is provided at the same pitch as, and reversely oriented (reversely phased) with respect to, the spiral blade 43a of the supply conveyance screw 31a. The rotation shafts 41a and 41b of the supply conveyance screw 31a and the agitation conveyance screw 31b, respectively, are rotatably supported on wall portions of the developing container 30 at the both end sides in the longitudinal direction.

Further, the rotation shaft 41b of the agitation conveyance screw 31b has, in addition to the spiral blade 43b, a regulation portion 52 and a discharge blade 53 which are formed integral therewith.

The regulation portion 52 is provided to stop the developer conveyed to the downstream side in the agitation conveyance chamber 30c, and to convey the developer to the developer discharge portion 30e when the amount of the developer exceeds a predetermined value. The regulation portion 52 is a spiral blade that is reversely oriented (reversely phased) with respect to the spiral blade 43b, that has substantially the same external diameter as the spiral blade 43b, and that is formed at a smaller pitch than the spiral blade 43b. Between the interior wall portion of the developing container 30 and an outer circumferential edge of the regulation portion 52, a gap of a predetermined size is formed. Through this gap, the surplus part of the developer is discharged to the developer discharge portion 30e.

The rotation shaft 41b extends to inside the developer discharge portion 30e. The portion of the rotation shaft 41b existing inside the developer discharge portion 30e is provided with a discharge blade 53. The discharge blade 53 is formed as a spiral blade that is oriented to the same direction as the spiral blade 43b, that is disposed at a smaller pitch than the spiral blade 43b, and that has a smaller external diameter than the spiral blade 43b. Thus, when the rotation shaft 41b rotates, the discharge blade 53 rotates as well, such that the surplus part of the developer that has been conveyed over the regulation portion 52 into the developer discharge portion 30e is further conveyed to the left side in FIG. 6, to be discharged to outside the developing container 30. The discharge blade 53, the regulation portion 52, and the spiral blade 43b are formed of a synthetic resin to be integral with the rotation shaft 41b.

At an exterior wall of the developing container 30, there are disposed gears 61 to 64. The gears 61 and 62 are firmly fixed to the rotation shaft 41a, the gear 64 is firmly fixed to the rotation shaft 41b, and the gear 63 is rotatably held in the developing container 30 and meshes with the gears 62 and 64.

In a case of development performed without new supply of developer, when the gear 61 is driven to rotate by a driving source such as a motor, the supply conveyance screw 31a rotates to convey the developer existing inside the supply conveyance chamber 30b in a direction indicated by arrow P, through the developer passage 40a, into the agitation conveyance chamber 30c. Furthermore, the driving force of the supply conveyance screw 31a is transmitted to the agitation conveyance screw 31b via the gears 62 to 64, and when the agitation conveyance screw 31b rotates, the developer existing in the agitation conveyance chamber 30c is conveyed in a direction indicated by arrow Q. Thus, the developer is conveyed from the supply conveyance chamber 30b through the upstream-side developer passage 40a into the agitation conveyance chamber 30c, drastically changing its heap height, and is conveyed, without moving over the regulation portion

12

52, through the downstream-side developer passage 40b, into the supply conveyance chamber 30b.

In this way, the developer is agitated while circulating from the supply conveyance chamber 30b, to the developer passage 40a, the agitation conveyance chamber 30c, and the developer passage 40b, and the thus agitated developer is supplied to the magnetic roller 32.

Next, a description will be given of a case where new developer is added from the developer supply port 30d. When 10 the toner is consumed in development, the developer including the toner and the carrier is added from the developer supply port 30d into the supply conveyance chamber 30b.

The added developer is, in the same manner as in development, conveyed by the supply conveyance screw 31a in the 15 direction indicated by arrow P inside the supply conveyance chamber 30b, and thereafter, the added developer is conveyed through the upstream-side developer passage 40a into the agitation conveyance chamber 30c. Furthermore, the developer existing inside the agitation conveyance chamber 30c is 20 conveyed by the agitation conveyance screw 31b in the direction indicated by arrow Q. When the regulation portion 52 rotates along with the rotation of the agitation conveyance screw 31b, the restriction portion 52 gives the developer a 25 transporting force in a direction opposite to the direction (indicated by arrow Q) in which the developer is transported by the spiral blade 43b. The developer is stopped by the regulation portion 52 into a high heap, and surplus part of the developer moves over the regulation portion 52 to be discharged via the developer discharge portion 30e to the outside 30 of the developing container 30.

FIG. 7 is a perspective view of a developer recovering mechanism 80 in the image forming apparatus 100 of the first embodiment. Note that the developing devices 3a to 3d are not illustrated in FIG. 7. The developer recovering mechanism 80 has a conveyance pipe 82 inside which a conveyance screw (not shown) is disposed, and a recovery container 83 for storing the developer conveyed thereto through the conveyance pipe 82. The recovery container 83 is accommodated in a drawable tray 84. The conveyance pipe 82 has connection portions 82a to 82d connected to the developer discharge portions 30e (see FIG. 6) of the developing devices 3a to 3d, respectively.

In the present embodiment, when the developing devices 3a to 3c disposed in the magenta, cyan, and yellow image forming sections Pa to Pc shown in FIG. 4 and the developing device 3d disposed in the black image forming section Pd shown in FIG. 5 are installed in the image forming apparatus 100, respective positional relationships between the rotation shafts of the photosensitive drums 1a to 1d and the rotation shafts 41b of the agitation conveyance screws 31b of the developing devices 3a to 3d corresponding to the photosensitive drums 1a to 1d, respectively, are all the same.

Specifically, as shown in FIG. 8, when the developing rollers 33 of the developing devices 3a to 3c and the magnetic roller 32 of the developing device 3d are disposed at respective predetermined positions facing the photosensitive drums 1a to 1d, the rotation shafts 41b of the agitation conveyance screws 31b of the developing devices 3a to 3d are disposed in the same direction (lower left direction in FIG. 8) as seen from, and at the same distance from, rotation shafts O of the photosensitive drums 1a to 1d, respectively.

As shown in FIG. 6, the developer discharge portion 30e is provided on an extension of the rotation shaft 41b of the agitation conveyance screw 31b. That is, the developer discharge portions 30e of the developing devices 3a to 3d are disposed in the same positional relationship with respect to the photosensitive drums 1a to 1d, respectively. Furthermore,

the positional relationships between the rotation shafts O of the photosensitive drums **1a** to **1d** disposed in the image forming sections **Pa** to **Pd** and the connection portions **82a** to **82d** of the developer recovery mechanism **80** corresponding to the photosensitive drums **1a** to **1d**, respectively, are all the same in the image forming sections **Pa** to **Pd**.

With this configuration, in a case, for example, where specifications of the image forming apparatus **100** is such that a black image is formed in the image forming section **Pa**, by incorporating the developing device **3d** employing the first developing method in the image forming section **Pa**, it is possible to securely connect the developer discharge portion **30e** of the developing device **3d** to the connecting portion **82a** of the developer recovery mechanism **80**. Likewise, when it is desired to change the order of the image forming sections forming cyan, magenta, and yellow images, by merely changing the order of the developing devices **3a** to **3c**, it is possible to securely connect the developer discharge portions **30e** of the developing devices **3a** to **3c** to the connecting portions **82b** to **82d**, respectively, of the developer recovery mechanism **80**.

Thus, the developing device **3d** employing the first developing method and the developing devices **3a** to **3c** employing the second developing method can be incorporated freely in any of the image forming sections **Pa** to **Pd**, and this helps enhance the degree of freedom in design and layout of the image forming apparatus **100**. Moreover, it is possible to achieve common specifications of the developing devices **3a** to **3d** and the developer recovering mechanism **80**, and this helps reduce the number of components and achieve simple management of components. Furthermore, it is possible to achieve a common assembling process, and this helps reduce production cost.

It should be noted that, although, in the present embodiment, where the developer discharge portion **30e** is disposed on the same shaft with the agitation conveyance screw **31b**, the rotation shafts of the photosensitive drums **1a** to **1d** and the rotation shafts **41b** of the agitation conveyance screws **31b** of the developing devices **3a** to **3d** corresponding to the photosensitive drums **1a** to **1d**, respectively, are disposed to be in the same positional relationship, it is also possible to dispose the developer discharge portion **30e** and the supply conveyance screw **31a** on the same shaft. In this case, respective positional relationships between the rotation shafts O of the photosensitive drums **1a** to **1d** and the rotation shafts **41a** of the supply conveyance screws **31a** of the developing devices **3a** to **3d** corresponding to the photosensitive drums **1a** to **1d**, respectively, are all the same.

Alternatively, the developer discharge portions **30e** of the developing devices **3a** to **3c** may each be disposed on the same shaft with the supply conveyance screw **31a**, and the developer discharge portion **30e** of the developing device **3d** may be disposed on the same shaft as the agitation conveyance screw **31b**. In this case, as shown in FIG. 9, positional relationships between the rotation shafts O of the photosensitive drums **1a** to **1c** and the rotation shafts **41a** of the supply conveyance screws **31a** of the developing devices **3a** to **3c** corresponding to the photosensitive drums **1a** to **1c**, respectively, and a positional relationship between the rotation shaft O of the photosensitive drum **1d** and the rotation shaft **41b** of the agitation conveyance screw **31b** of the developing device **3d** corresponding to the photosensitive drum **1d** are the same.

That is, the rotation shafts **41b** or the rotation shafts **41a** of the agitation conveyance screws **31b** or the supply conveyance screws **31a**, respectively, of the developing devices **3a** to **3d** where the developer discharge portions **30e** are provided

are located in the same direction as seen from, and at the same distance from, the rotation shafts O of the photosensitive drums **1a** to **1d**.

FIG. 10 is a side sectional view of the developing device **3d** employed in the image forming device **100** of a second embodiment of this disclosure. In the developing device **3d** employed in the present embodiment, like in the developing devices **3a** to **3c** (see FIG. 4), the supply conveyance chamber **30b** and the agitation conveyance chamber **30c** are horizontally disposed inside the developing container **30**. Also, the supply conveyance screw **31a** inside the supply conveyance chamber **30b** and the agitation conveyance screw **31b** inside the agitation conveyance chamber **30c** are also horizontally disposed. Note that the other portions of the developing device **3d** and the developing devices **3a** to **3c** are configured in the same manner as those of the first embodiment. Further, the agitating portions of the developing devices **3a** to **3d** and the developer recovery mechanism **80** are also configured in the same manner as those of the first embodiment, and thus, descriptions thereof will be omitted.

In the present embodiment, when the developing devices **3a** to **3c** shown in FIG. 4 and the developing device **3d** shown in FIG. 10 are placed in the image forming apparatus **100**, respective positional relationships between the rotation shafts O of the photosensitive drums **1a** to **1d** and the rotation shafts **41a** of the supply conveyance screws **31a** and the rotation shafts **41b** of the agitation conveyance screws **31b** of the developing devices **3a** to **3d** corresponding to the photosensitive drums **1a** to **1d**, respectively, are all the same.

Specifically, as shown in FIG. 11, when the developing rollers **33** of the developing devices **3a** to **3c** and the magnetic roller **32** of the developing device **3d** are disposed at respective predetermined positions facing the photosensitive drums **1a** to **1d**, the rotation shafts **41a** of the supply conveyance screws **31a** and the rotation shafts **41b** of the agitation conveyance screws **31b** of the developing devices **3a** to **3d** are disposed in the same direction (lower left direction in FIG. 11) as seen from, and at the same distance from, the rotation shafts O of the photosensitive drums **1a** to **1d**, respectively.

Further, as shown in FIG. 6, the developer discharge portion **30e** is provided on an extension of the rotation shaft **41b** of the agitation conveyance screw **31b**. That is, the developer discharge portions **30e** of the developing devices **3a** to **3d** are disposed in the same positional relationship with respect to the photosensitive drums **1a** to **1d**, respectively.

With this configuration, in a case, for example, where specifications of the image forming apparatus **100** are such that a black image is formed in the image forming section **Pa**, by installing the developing device **3d** employing the first developing method in the image forming section **Pa**, it is possible to securely connect the developer discharge portion **30e** of the developing device **3d** to the connecting portion **82a** of the developer recovery mechanism **80**.

Thus, like in the first embodiment, the developing device **3d** employing the first developing method and the developing devices **3a** to **3c** employing the second developing method can be installed freely in any of the image forming sections **Pa** to **Pd**, and this helps enhance the degree of freedom in design and layout of the image forming apparatus **100**. Moreover, it is possible to achieve common specifications of the developing devices **3a** to **3d** and the developer recovering mechanism **80**, and this helps reduce the number of components and achieve simple management of components. Furthermore, it is possible to achieve a common assembling process, and this helps reduce production cost.

Moreover, in the present embodiment, positional relationships between the rotation shafts **41a** of the supply convey-

15

ance screws **31a** of the developing devices **3a** to **3d** and the photosensitive drums **1a** to **1d**, respectively, are all the same. Thus, in a case also where the developer discharge portions **30e** of the developing devices **3a** to **3d** are each provided on an extension of the rotation shaft **41a** of the corresponding supply conveyance screw **31a**, when installation positions of the developing devices **3a** to **3d** are changed, the developer discharge portions **30e** of the developing devices **3a** to **3d** can be securely connected to the connection portions **82a** to **82d** of the developer recovery mechanism **80**.

It should be understood that the present disclosure is not limited to the above embodiments, and various modifications are possible within the scope of the present disclosure. For example, the present disclosure is applicable not only to the color printer as shown in FIG. 1 but also to other color image forming apparatuses where developing devices employing first and second developing methods are co-resident, such as a color copier and a color multi-functional machine (that has functions of a copier, a facsimile, a scanner, and the like, and is referred to also as a multi-function peripheral (MFP)).

The present disclosure is applicable not only to color image forming apparatuses provided with a plurality of image forming sections but also to monochrome image forming apparatuses provided only with a black image forming section, such as a monochrome printer, a monochrome copier, and a monochrome digital multi-functional machine. With such a monochrome image forming apparatus as well, it is possible to selectively use two kinds of development methods according to a user's with a configuration where developing devices employing first and second developing methods are installable with compatibility.

The present disclosure is applicable to an image forming apparatus capable of compatibly incorporating a plurality of developing devices employing different developing methods. Use of the present disclosure makes it possible to achieve common specifications of the developing devices and the developer recovering mechanism, and thus to freely install two kinds of developing devices provided with a developer recovery mechanism and employing different developing methods; thus, it is possible to provide an image forming apparatus capable of reducing the number of components and simplifying the management of components.

What is claimed is:

1. An image forming apparatus, comprising: an image carrier on which an electrostatic latent image is formed;

a developing device provided corresponding to the image carrier, the developing device including: a developing container for accommodating a two-component developer including a magnetic carrier and toner; a developer carrier rotatably supported in the developing container;

an agitation member that agitates and conveys the developer in the developing container;

a supply member that agitates and conveys the developer received from the agitation member and supplies the developer to the developer carrier;

a developer supply port through which the developer is supplied into the developing container; and

a developer discharge portion that discharges a surplus part of the developer out of the developing container,

the developing device developing the electrostatic latent image formed on the image carrier into a toner image, an image forming section including the image carrier and the developing device; and

a developer recovery mechanism that has a connection portion connected to the developer discharge portion,

16

and recovers the surplus part of the developer discharged from the developing device, the image forming section selectively incorporating either one of

a first developing device employing a first developing method where toner is caused to adhere to a surface of the image carrier by means of a magnetic brush formed on the developer carrier and

a second developing device having a toner carrier disposed between the developer carrier and the image carrier, and employing a second developing method where a toner layer is formed on a surface of the toner carrier by means of a magnetic brush formed on the developer carrier and toner is caused to adhere to the surface of the image carrier by means of the toner layer formed on the toner carrier,

wherein

in the first developing device and in the second developing device, the developer discharge portion is provided on a same shaft as either one of the agitation member and the supply member; and

in the first developing device and the second developing device installed in the image forming section, a rotation shaft of whichever of the agitation member and the supply member of one of the first developing device and the second developing device is provided with the developer discharge portion is disposed in a same direction as seen from, and at a same distance from, the rotation shaft of the image carrier as the rotation shaft of whichever of the agitation member and the supply member of another one of the first developing device and the second developing device is provided with the developer discharge portion.

2. The image forming apparatus of claim 1,

wherein

in the first developing device and the second developing device, the developer discharge portion is provided on a same shaft as the agitation member; and

in the first developing device and the second developing device installed in the image forming section, a rotation shaft of the agitation member of the first developing device is disposed in a same direction as seen from, and at a same distance from, the rotation shaft of the image carrier as a rotation shaft of the agitation member of the second developing device.

3. The image forming apparatus of claim 1,

wherein,

in the first developing device and the second developing device, the developer discharge portion is provided on a same shaft as the supply member; and

in the first developing device and the second developing device installed in the image forming section, a rotation shaft of the supply member of the first developing device is disposed in a same direction as seen from, and at a same distance from, the rotation shaft of the image carrier as a rotation shaft of the supply member of the second developing device.

4. The image forming apparatus of claim 1,

wherein

the image forming section includes a plurality of image forming sections that all have a same positional relationship between a rotation shaft of the image carrier and the connection portion of the developer recovery mechanism corresponding to the image carrier.

5. An image forming apparatus, comprising:

an image carrier on which an electrostatic latent image is formed;

17

a developing device provided corresponding to the image carrier, the developing device including:
 a developing container for accommodating a two-component developer including a magnetic carrier and toner;
 a developer carrier rotatably supported in the developing container;
 an agitation member that agitates and conveys the developer in the developing container;
 a supply member that agitates and conveys the developer received from the agitation member and supplies the developer to the developer carrier;
 a developer supply port through which the developer is supplied into the developing container; and
 a developer discharge portion that discharges surplus part of the developer out of the developing container, the developing device developing the electrostatic latent image formed on the image carrier into a toner image, an image forming section including the image carrier and the developing device; and
 a developer recovery mechanism that has a connection portion connected to the developer discharge portion, and recovers the surplus part of the developer discharged from the developing device,
 the image forming section selectively incorporating either one of
 a first developing device employing a first developing method where toner is caused to adhere to a surface of the image carrier by means of a magnetic brush formed on the developer carrier and

5

10

15

20

25

18

a second developing device having a toner carrier disposed between the developer carrier and the image carrier, and employing a second developing method where a toner layer is formed on a surface of the toner carrier by means of a magnetic brush formed on the developer carrier and toner is caused to adhere to the surface of the image carrier by means of the toner layer formed on the toner carrier,
 wherein
 the developer discharge portion is provided on a same shaft as either one of the agitation member and the supply member in both of the first developing device and the second developing device; and
 in the first developing device and the second developing device installed in the image forming section, rotation shafts of the agitation member and the supply member of one of the first developing device and the second developing device are disposed in same directions as seen from, and at same distances from, the rotation shaft of the image carrier as rotation shafts of the agitation member and the supply member of another one of the first developing device and the second developing device.

6. The image forming apparatus of claim 5,

wherein

the image forming section includes a plurality of image forming sections that all have a same positional relationship between a rotation shaft of the image carrier and the connection portion of the developer recovery mechanism corresponding to the image carrier.

* * * * *
